UNITED STATES PATENT OFFICE

EBER B. HORNE, OF EAST CLEVELAND, OHIO

RUG-HANGING APPARATUS

Application filed January 12, 1928. Serial No. 246,350.

This invention relates to rug hanging apparatus, particularly that which is used in rug cleaning establishments to support the rugs while they are being dried. For this purpose, it has been customary to mount a row of pins in a wooden pole, then to fasten the rug over the pins, and thereafter to support the pole sufficiently high above the floor that the bottom of the rug clears the floor.

10 While the rug is so supported, there is a tendency of the pole to bend, and as a result, the rug will not lay flat upon the floor after it has been dried.

Moreover, the pole is apt to split, particularly along the line of attachment between the pole and the supporting pins. As a result, the eye bolts which connect the pole to the supporting ropes are apt to be pulled away from the pole, thus allowing the rug 20 to fall.

The principal object of the present invention is to make a pole upon which one or more rugs may be readily fastened and which will not be deflected by the weight of a large 25 rug. A further object is to make a pole which will not have a tendency to split, and which therefore will not permit a rug to fall from the pole.

In the drawings, Fig. 1 is a side view of a 30 rug which is suspended from a pole made in accordance with my invention; Fig. 2 is an end view of the device shown in Fig. 1; Fig. 3 is a side elevation of parts of the pole on an enlarged scale; Fig. 4 is a vertical trans- 35 verse plane taken through the pole on a plane indicated by the line 4—4 in Fig. 3; Figs. 5 and 6 are end and side views respectively of a pole having a modified form of attachment for enabling the pole to be connected to hoist- 40 ing ropes.

Rug hanging apparatus of this character usually includes some form of means for holding the pole in suspended position during the drying operation. Accordingly, in 45 Figs. 1 and 2 I have shown hangers 10, each of which supports a pulley sheave 12, over which a rope 13 may be passed. The upper end of each rope is attached to a hook member 14, which is intended to be fastened 50 through an eye member to the pole.

The pole illustrated in the drawings is made of two pieces of wood 15 and 16, which are suitably rounded on the top to receive rug retaining pins 17, and which are intended to be fastened together, as by securing screws 55 18. The joint between the two blocks extends in a vertical plane through the middle of the pole, as is illustrated particularly in Fig. 5. Each block is provided with a semi-circular recess 20, and the recesses are so positioned 60 that a cylindrical passageway is provided through the pole when the blocks are brought together. A pipe 21 is placed within such passageway and functions to add rigidity to the pole, and to prevent deflection without 65 increasing the weight of the pole to an objectionable degree.

In Figs. 3 and 4, I have shown the eye member as embodying a bolt 25 which extends through the pole and pipe. The upper 70 portion of the bolt is curved, as at 26, and the free end is intended to enter a recess in the top of the pole. Thereafter, the bolts may be locked in place by means of nuts 27 which bear against a channel-shaped strip 28. I 75 place one of these eye members at each end of the pole, as is illustrated in Fig. 1.

A modified form of construction which may be employed for making the eye member, is shown in Figs. 5 and 6. Such modification consists in two metallic strips which extend vertically along the sides and top of the respective members 15 and 16. Each of the strips 30 and 31 has a curved extension 32 which, when brought into engagement 80 with each other, provide a passageway 33, through which the hook member may extend. These strips may be fastened to the pole by bolts 35 which are disposed above and beneath the pipe. 85

A pole made in accordance with my invention is advantageous, in that it will hold extremely heavy rugs without deflecting, and still will be exceptionally light in weight.

I claim:—

1. A rug hanging pole comprising in combination a pair of complementary shaped strips having contiguous faces lying in a vertical plane and extending throughout the length of the pole, a cylindrical reinforcing 100

- member lying partially within each strip and also extending throughout the length of the pole, a pair of straps at each end of the pole, means for attaching said straps to the pole above and below the reinforcing member, said straps cooperating to provide a pole supporting eye, and pins extending from each of said strips at spaced intervals adjacent the upper part of the pole.
- 5 2. In a device of the character described, the combination with a pole, of a hollow supporting member extending therethrough and throughout the length thereof, a pair of co-operating pole supporting members at each 10 end of the pole, said members being attached to the sides of the pole and projecting above the top portion thereof, the projecting portions cooperating to provide a pole supporting eye.
- 15 3. In a device of the character described, the combination with a pair of similarly shaped strips arranged back to back to form a pole, means for holding said strips together, and other means at the ends of the strips for 20 enabling the pole to be suspended in overhead position, said last named means comprising vertically extending straps, each having the upper portion thereof curved in opposite directions, said curved portions co- 25 operating to provide an eye through which pole supporting means may extend.
- 25 4. In a rug hanging apparatus, the combination of a pole having a row of rug supporting pins in the upper surface thereof, a stiff 30 tube extending lengthwise thereof substantially from end to end and snugly embedded in the material of the pole to reinforce the same, and supporting devices tightly secured to the pole adjacent each end and having portions extending beneath the reinforced pole.
- 35 40 In testimony whereof, I hereunto affix my signature.

EBER B. HORNE.
